UNITED STATES PATENT OFFICE

ROBERT E. McELROY, OF JACKSON, MICHIGAN, ASSIGNOR TO REYNOLDS SPRING COMPANY, OF JACKSON, MICHIGAN

SPRING STRUCTURE

Application filed January 18, 1930. Serial No. 421,767.

This invention relates to spring structures, designed particularly for automobile seats.

It is the custom in this art to provide the spring structures with an overhang at the front and rear upper edge of the structure, and generally this is accomplished by having the upper frame project forwardly and rearwardly beyond the front and rear of the base frame of the structure, with the front and rear rows of springs connected by a wire having its ends connected to the ends of the upper frame, and this wire is generally offset by the formation of kinks or bends which bridge the space between such wire and the frame, and clips are used to connect the offsets to the upper frame. This necessitates providing the offsets under certain specifications, according to the size or model of the spring structure, which requires time and more or less accuracy in the formation of the offsets as well as the employment of separate clips for securing the offsets to the structure.

It is, therefore, one object of the present invention to provide a clip constructed in order to obviate the present practice of kinking, bending, or offsetting at intervals the upper frame wire or the usual wire which cooperates therewith for the provision of the usual overhang at the front and rear upper edge of spring seat structures, and to utilize this clip for the securing of the adjacent end of diagonal or horizontal stay wires to eliminate the employment of a separate clip to secure such end of such stay wires.

Another object is to provide a clip designed to bridge the space between the usual wire which cooperates with the upper frame to form an overhang and to provide such clip in such a manner that it may perform not only this stated function but also the function of securing a stay wire, which may be formed of a size adaptable for varying spaces between the frame wire and the cooperating wire, whereby to enable the manufacture of these clips in one or more sizes required, and accumulation of them in stock as a standard part, to overcome the difficulties experienced in the use of the adjacent offsets, which have to be made to pattern and which are not interchangeable.

With the above and other objects in view, the invention consists in the construction and novel combination and arrangement of parts hereinafter fully described, illustrated in the accompanying drawings, and set forth in the claims hereto appended, it being understood that various changes in the form, proportion, and minor details of construction, within the scope of the claims, may be resorted to without departing from the spirit of the invention or sacrificing any of the advantages thereof.

In the drawings:

Figure 1 is a top plan view of the invention.

Fig. 2 is a vertical transverse sectional view on the line 2—2 of Fig. 1.

Fig. 3 is a similar view on the line 3—3.

Referring now more particularly to the accompanying drawings, the reference character 1 indicates a base frame of any suitable character but shown as of U-shape in cross section, and 2 indicates an upper frame of wire or other suitable material, 3 indicating springs of any suitable type mounted on suitable supporting bars 4.

The upper frame overhangs the base frame at the front and rear of the structure, and straight wires 5 and 6 extend from end to end of the upper frame in spaced relation to the front and rear of the upper frame and substantially in vertical alignment with the front and rear of the base frame, and to these wires 5 and 6 the front and rear rows of springs are secured at their upper ends as at 7, leaving an overhang at the upper edge of the front and rear of the structure. The ends of these wires 5 and 6 are bent laterally as at 8, and these bent ends are secured by clips 9 to the ends of the upper frames.

Clips A are adapted to bridge the space between each straight wire 5—6 and the adjacent edge of the upper frame, these clips being arranged at intervals in spaced relation, as shown. Each clip is formed alike and each consists of a body portion 10 having one end bent back upon itself as at 11 to embrace the respective wire 5—6 and having its opposite end bent back upon itself as at 12 to embrace the front or the rear of the upper frame as the case may be, and also to 100

embrace the laterally bent end 13 of a diagonal stay 14 which extends across the clip A and over the wire 5 from which the diagonal stay extends downwardly and has its laterally directed end 15 fitted in the U-shaped base frame 1 and pinched therein, as shown at 16.

The clips A are serviceable for connecting horizontal stays 17 to the wires 5 and 6 and the front and rear portions of the upper frame, as for instance, the laterally directed ends 18 of the horizontal stays 17 are connected to the clips A in the same manner that the forward end of the diagonal stay 14 is connected to the clip A. Further description of this connection of the horizontal stays 17 seems unnecessary. It might be noted, however, that the clips A might be reversed and the diagonal stays have their forward ends connected thereto from the under side rather than on the upper side, as indicated at C', and as a matter of fact, as is obvious, both ends of the horizontal stays may be connected to the under side of the clips C—C' at both ends, if desired.

From the foregoing it will be seen that in the use of the clips A and C', which are formed alike, these clips may be kept in various sizes in stock, and that by virtue of the mounting hereinbefore described, it is not necessary to kink or bend or otherwise offset the wires 5—6 or the front and rear wire portions of the upper frame, and yet an effectual connection between such elements is obtained to prevent any hinge action incident to pressures or stresses occasioned by the weight of the occupant.

What is claimed is:

1. In a spring structure, a base frame, an upper frame, rows of springs mounted between said frames, the upper frame extending forwardly beyond the front of the base frame, a straight wire secured to the upper frame and extending in parallelism with the front of the upper frame, and spaced therefrom and secured to the front row of springs, stay wires arranged between rows of springs and having their forward ends engaging the front of the upper frame, and flat clips bridging the space between the front of the upper frame and said wire and secured to the frame and to said wire and also secured to the forward ends of the stay wires.

2. In a spring structure, a base frame, an upper frame, rows of springs arranged between said frames, the upper frame extending forwardly beyond the front of the base frame, a straight wire secured to the upper frame and extending in parallelism with the front of the upper frame and spaced therefrom and secured to the front row of springs, stay wires arranged between rows of springs and having their forward ends bent and lying in engagement with the front of the upper frame, and clips securing the front of

the upper frame and said wire and the forward bent ends of the stay wires together.

3. In a spring structure, a base frame, an upper frame which overhangs the base frame at the front and rear thereof, a wire secured to the upper frame near the front portion thereof vertically above the base frame and extending in parallelism with the front of the upper frame and spaced therefrom, a second wire secured to the upper frame in spaced relation to the rear of the upper frame and connected to the rear row of springs, clips connecting each of said wires with the respective front or rear portion of the upper frame, and stay wires having their ends connected to said clips.

4. In a spring structure, a base frame, an upper frame, springs arranged between the frames, the upper frame extending beyond the front of the base frame at one side of the latter, a straight wire secured to the upper frame and extending in parallelism with and spaced from the front of the upper frame, a stay wire having its forward end located adjacent the front of the upper frame, and a flat clip bridging the space between the front of the upper frame and said straight wire and secured to the frame and to said straight wire and also secured to the forward end of said stay wire.

In testimony whereof I have hereunto set my hand.

ROBERT E. McELROY.
